DESK TRAY FOR TYPISTS' ACCESSORIES

Louis P. Caldwell and Philipp C. Wohlt,
Independence, Mo.

Application March 23, 1953, Serial No. 24,161

Term of patent 14 years

(Cl. D74—1)

To all whom it may concern:

Be it known that we, Louis P. Caldwell and Philipp C. Wohlt, both citizens of the United States, and both residing at Independence, in the county of Jackson, and State of Missouri, have invented a new, original, and ornamental Design for a Desk Tray for Typists' Accessories, of which the following is a specification, reference being had to the accompanying drawing, forming a part thereof, wherein:

Fig. 1 is a front perspective view of a desk tray for typists' accessories, showing our new design,

Fig. 2 is a rear perspective view of the desk tray for typists' accessories shown in Fig. 1, and

Fig. 3 is a front elevational view thereof as it appears with the moistener element in detached position.

We claim:

The ornamental design for a desk tray for typists' accessories, as shown and described.

LOUIS P. CALDWELL,
PHILIPP C. WOHLT.
